UNITED STATES PATENT OFFICE

ASA H. HERRING, OF HAVERHILL, MASSACHUSETTS.

DESIGN FOR SHOE.

Specification forming part of Design No. 5,995, dated July 16, 1872.

To all persons to whom these presents may come:

Be it known that I, ASA H. HERRING, of Haverhill, of the county of Essex and State of Massachusetts, have invented a new, useful, and ornamental Design or Configuration for a Shoe or Slipper; and do hereby declare the same to be described as follows, and represented in the accompanying drawing, of which—

Figure 1 is a top view, and Fig. 2 a side elevation, of a shoe provided with the said configuration. It is of the kind termed the "opera slipper."

In carrying out my design the heel part is elevated so as to extend as high as the instep part, and with each of the quarters as sloped down, or has a curved slope, as shown at *a b c*, and from thence is curved about a quarter of a circle, as shown at *c d*, to meet the edge of the instep-lap *e*, formed as shown.

The configuration of the edge of the mouth of the shoe as shown, and of the rest of the shoe as represented, constitutes the design, which, besides being useful in making the shoe to be made with whole quarters and to better maintain its place in the heel of the wearer and prevent his pantaloons from catching in the upper edge of the heel part of the shoe, imparts to the shoe a pleasing ornamental appearance.

I claim—

The configuration of the shoe, as shown and described.

ASA H. HERRING.
